UNITED STATES PATENT OFFICE.

GEORGE C. CLARK, OF DETROIT, MICHIGAN, ASSIGNOR TO CHARLES F. FERGUSON AND HARRY C. WOODRUFF, TRUSTEES, BOTH OF DETROIT, MICHIGAN.

SWINGING STOP FOR SLIDABLE HINGED SASHES.

1,249,331.

Specification of Letters Patent. Patented Dec. 11, 1917.

Application filed May 11, 1916. Serial No. 96,776.

To all whom it may concern:

Be it known that I, GEORGE C. CLARK, a citizen of the United States, residing at Detroit, county of Wayne, State of Michigan, 5 have invented a certain new and useful Improvement in Swinging Stops for Slidable Hinged Sashes, and declare the following to be a full, clear, and exact description of the same, such as will enable others skilled 10 in the art to which it pertains to make and use the same, reference being had to the accompanying drawings, which form a part of this specification.

The object of this invention is to provide 15 a hinge stop that can be swung away from the window, so as to allow the sash to be swung inward for ventilating the room, or for cleaning the glass. Another object is to provide a stop that can be either fastened 20 or hinged at both ends to swing in a vertical or a horizontal plane and is for use in connection with a sliding hinged sash. These and other objects and the several novel features of the invention in its preferred form 25 are hereinafter more fully described and claimed and shown in the accompanying drawings in which,—

Figure 1 is a cross section through a window, showing the stop and the window in 30 dotted lines, when swung inward to ventilate the room.

Fig. 2 is a perspective detail of the hinge member at the bottom of the stop.

Fig. 3 is a detail of the pivot plate used 35 in connection with the hinge member in Fig. 2.

Fig. 4 is an enlarged view of the stop, certain parts being broken away and showing 40 the hinge member, the warping plate, and the pivot catch at the top of the stop.

Fig. 5 is a perspective view of one-half of 45 the pivot catch used at the top of the stop, carrying a binding nut and showing the stop to which it is fastened, in dotted lines.

Fig. 6 is a view of the other half of the pivot catch having a slot in which the binding nut in Fig. 5 engages, and showing 50 the frame to which it is fastened, in dotted lines.

Fig. 7 is a section through the warping plate.

Fig. 8 is a view of the removable parting 55 strip used between the upper and lower sashes of the window.

Similar characters refer to similar parts

throughout the drawing and specification.

The device consists of a window frame 1, of the thick wall or deep type in which the 60 upper sash 2 and the lower sash 3 slide, each sash being pivoted at the lower end thereof to the sash cord. The window frame is also provided with a stop 4 which is set in from the inner edge of the window and 65 is hinged at its lower end to the hinge 5, as is shown more particularly in Fig. 2.

The hinge 5 is fastened to the plate 6, which in turn is fastened to the hinge 7, which connects both the plates 6 and 8. This 70

hinge member is mounted directly on the base plate 9, shown more particularly in Fig. 75

3, which is screwed to the window frame, being provided with screw slots 10, which allow for adjustment thereof. The screw 11

passes through the washer 12 through the plate 8, and through the hole 13 in the plate 9. This forms a pivot, the plate 9 being solid with the window frame, and plate 8 being adapted to swing on the screw 11, as its axis. 80

At the top of the stop is provided the two pieces 14 and 15, which are mounted so as to slide one below the other. The stop in 85

its normal position brings the two parts together, as shown in Fig. 4, and the thumb-screw 30 in the part 14 can be turned up to bind the two parts 14 and 15 together. The part 15 is slotted at its forward end at 31, and is formed with the up-turned edge 16

on each side of the slot behind which the thumb-screw engages, thus preventing accidental displacement of the stop by the window bumping it and forcing it out of place. 90

As can be readily seen from the drawing, by loosening the thumb-screw 30 so that it can be moved over the projection 16 and out of the slot 31, the stop can be turned at right angles to the window frame, in the direction of the arrow in Fig. 1, or it can be 95

swung across the face of the window until it rests on the window sill, or by fastening the two parts 14 and 15 together, it can also be 100

swung on the screw 11 and the thumb-screw 30 as its hinges. In order to swing the stop on the vertical pivots the catch 22

and companion member 21 should not be used. The stop shown in the drawings is of 105

a type for use in a thick wall, and the distance from the sash to the inner edge of the window frame is too great to permit of the use of a stop of that width. In this type

110 of window, one of the best ways of remov-

ing the stop to allow the window to swing, is to hinge the stop as in this case, so it can be swung out of the window frame, or so that it can be swung across the face of the window frame and laid down upon the sill thereof, to allow a clear space in which the window can swing. I have shown in the drawing a method of pivoting this stop on the upper end on the thumb-screw 30, and at the lower end on the screw 11, so that it can be swung in a horizontal plane. This arrangement is intended for windows having a narrow space between the edge of the sash and the inner edge of the window so that when swung on the pivots 11 and 30 as its vertical axis, it can be folded back outside of the window frame and thus allow a clear space in which the window can be swung. When the stops are out of the way, it being understood that there is a stop at each side of the window, the window can be swung inwardly, the direction for swinging the window being shown in dotted lines in Fig. 1. If it is necessary to remove the upper sash it can be slid to its lowermost position, at which point the parting strip 17 between the two windows can be removed, there being a parting strip 17 at both sides of the window frame, and thus the sash 2 can be swung to the same position as the lower sash, it also being pivoted at its lower end to the sash cord. This parting strip 17 has a pin 18 at the upper end thereof, and a pin 19 at the lower end thereof, which fit in sockets in the window frame. The lower cross bar of the upper frame projects outward over the parting strip 17 in its normal position, and prevents removal thereof. When the projecting cross bar of the window frame passes low enough to cover the solid part 20 of the parting strip, the pin 18 can be removed from its socket in the window frame by swinging the stop 17 outward across the window frame and then lifting it up to disengage the pin 19 from its socket. The window sash then can be swung inwardly as there are no projections on which it would catch. In cases where the window sashes are very long, it can be seen that the hinged stop must also be very long and is liable to warp. To prevent this, a plate 21 is fastened to the window frame, the window frame being cut out directly below it to provide a space for the hooked end 22 of the plate 23, which is fastened to the stop 4, this catch holding the stop and binding it in a position parallel with window frame 1 and preventing it from warping.

One of the novel features of this invention is embodied in the hinged joint, Fig. 2, which allows the stop to be swung across the face of the window frame, or at a right angle to it, or it can be swung in a horizon-

tal plane on the point 11 and the thumb-screw 30. Another novel feature is that the window can be swung inwardly, enabling the operator to clean the outside face of the glass, thus eliminating the troublesome and dangerous belts or ladders, which are commonly used for this purpose, and prevents the danger of anyone falling from the window from the necessity of climbing outside to clean it.

From the foregoing description, it becomes evident that the device is comparatively simple, affords a splendid means of ventilation, and is very simple, efficient and convenient in operation.

Having thus briefly described my invention, its utility and mode of operation, what I claim and desire to secure by Letters Patent of the U. S., is—

1. In a window frame, a sash, a stop provided to form a surface against which the sash bears, said stop being provided with a hinged joint adapted to allow movement of the sash in a vertical plane at right angles with the window, and in a vertical plane parallel with the window frame, and means for pivoting the stop to swing in a horizontal plane.

2. In a window frame, a vertically disposed stop provided with a hinged joint at the bottom thereof, said hinged joint being pivoted to the window frame on a vertical axis and adapted to swing in a horizontal plane, said hinged joint being also provided with hinges adapted to allow the stop to be swung at a right angle to either of the hinges and a plate mounted directly beneath the hinged joint and fastened to the window frame and providing a bearing for the pivot to which the hinged joint is fastened.

3. In a window frame, a vertically disposed stop provided with a hinged joint at the bottom thereof, said hinged joint being pivoted to the window frame on a vertical axis and adapted to swing in a horizontal plane, said hinged joint being also provided with hinges adapted to allow the stop to be swung at a right angle to either of the hinges and a plate mounted directly beneath the hinged joint and fastened to the window frame and providing a bearing for the pivot to which the hinged joint is fastened, and at the upper end of the stop a fastening plate solidly mounted thereon, carrying a thumb-screw adapted to engage in a longitudinally disposed slot in a similar plate mounted on the window frame in such manner as to allow movement of the plates one below the other.

In testimony whereof, I sign this specification.

GEORGE C. CLARK.
